UNITED STATES PATENT OFFICE

2,443,120

ADDITIONAL FUEL SUPPLY FOR INTERNAL-
COMBUSTION ENGINES

David R. Saucier, Bossier City, La.

Application January 5, 1945, Serial No. 571,410

3 Claims. (Cl. 123—121)

1

This invention relates to so-called fuel-saving devices such as auxiliary feeding and supplying attachments of types applicable to conventional internal combustion engines, for example, the forms used on present day automobiles and the like.

More particularly, the invention has to do with ways and means of utilizing the suction of the engine in the intake manifold to pick up and deliver added gasoline vapors and air from the stock filler pipe on the gasoline storage tank, this constituting a source of highly combustible fuel which is properly piped and delivered into the intake manifold.

In addition to the broad idea of providing a delivery conduit between the tank filler pipe and intake manifold, I have evolved and produced a simple and expedient accelerator-controlled regulator, this admitting the extra or additional fuel depending on the speed of the motor and the intensity of the suction developed as the motor speed picks up.

Other features and advantages will become more readily apparent from the following description and the accompanying illustrative drawings.

In the drawings, wherein like numerals are employed to designate like parts throughout the views:

Figure 1 is an elevational view showing the intake manifold, carburetor, fragmentary portion of the gasoline storage tank, the filler neck and the invention, the fuel saver, between the filler neck and intake manifold.

Figure 2 is a longitudinal sectional view through the control valve device.

Figure 3 is a fragmentary view with the valve removed to expose the progressively uncovered extra fuel inlet ports.

Referring now to the drawings by distinguishing reference numerals, it will be seen that the gasoline storage tank A is provided with the customary filler neck B, this having a suitably vented cap C. The carburetor is denoted at D and the intake manifold at E. The crank arm F for controlling the throttle valve is indicated at F and the accelerator push-pull rod is denoted at G. These are all old and conventional parts, with which the invention is associated directly and indirectly.

I first call attention to the valve-controlled automatic regulator unit 4. This comprises a cylinder 5 having a suitable cap 6 at one end in which a reciprocating valve rod 7 is mounted. The outer end of the rod is provided with an

upturned crank 8 which is connected with a link 9, the latter in turn being connected, as at 10, to the push-pull accelerator rod G. The inner end of this rod, that is, the end located in the cylinder, is provided with a valve head 11 adjustably mounted in position and provided with packing cups 12 in movable sweeping contact with the bore of the cylinder. A lateral nipple 13 is provided intermediate the ends of the cylinder and this provides the desired connection for the feed line or pipe 14, the latter being connected in any suitable manner, as at 15, to the intake manifold E. A diaphragm is located between the nipple and cylinder, which diaphragm 16 is provided with a plurality of selectively usable and uncoverable additional fuel supply ports 16 (see Fig. 3).

I now call attention to an L-shaped elbow or fitting 17, this having a screw-threaded coupling 20 which is tapped into the adjacent screw-threaded end of the cylinder 5. The main branch is provided with a tool nut 18. The lateral outer branch 19 is suitably constructed to facilitate connection thereto of one end of the additional fuel pick-up and delivery line or pipe 20. This, as shown in Figure 1, has its intake end connected in any suitable manner, as at 21, with the capped filler neck B.

It is obvious that when the engine is operating, 30 the suction draws the accumulated gas fumes and vapors and admixed air from the chamber in the filler pipe, where considerable gases accumulate. The thus accumulated gases are drawn through the pipe and elbow 17 into the cylinder 15, the same passing through the pipe 14 by way of the valved nipple construction 13. The operation is automatic and the amount of fuel taken in at this point depends on the speed of the engine. When the foot accelerator pedal (not shown) is 40 pushed down, it operates the rod G and the rod G controls the sliding movement of the valve 11 by way of the link 9 and associated valve rod 7. The faster the speed of the motor, and the lower the foot pedal, the more the valve 11 is open. 45 In other words, at certain speeds, all four ports 16 are uncovered by the valve. When, however, the speed is reduced, only one or two ports are open. Consequently, the amount of additional fuel drawn into the intake manifold depends on 50 the accelerator pedal action.

In practice, a suitable bracket 22 is provided to suspend the cylinder 5, said bracket having an appropriate attaching arm 23 mounted on the manifold structure.

It is believed that this invention fulfills the re-

uirements of a long-felt need for conserving of fuel by utilizing otherwise wasted gasoline tank vapors. In addition, the efficiency of the device is brought to its highest degree of operation by the automatic accelerator-actuated and controlled regulating valve means.

A careful consideration of the foregoing description in conjunction with the invention as illustrated in the drawings will enable the reader to obtain a clear understanding and impression of the alleged features of merit and novelty sufficient to clarify the construction of the invention as hereinafter claimed.

Minor changes in shape, size, materials and rearrangement of parts may be resorted to in actual practice so long as no departure is made from the invention as claimed.

I claim:

1. An automotive accessory in the form of an additional fuel supply for the intake manifold of an internal combustion engine comprising a manifold attachment embodying a cylinder, said cylinder being provided intermediate its ends with a laterally extending multiple ported neck, said neck being adapted to accommodate a discharge pipe which pipe in turn is adapted to be connected at one end with the neck, and at its opposite end with the intake manifold, an elbow detachably threaded into the intake end of said cylinder, said elbow being adapted to accommodate a fuel supply pipe which pipe is adapted for connection at one end with the elbow and at its opposite end with the filler cap of a conventional gasoline storage tank, a cutoff and reg-

ulating valve slidably mounted in said cylinder and coacting with the ports in said neck, an operating rod connected with said valve, and means for connecting the outer end of the rod with a throttle valve actuating rod in order that the throttle valve and sliding valve may be simultaneously controlled.

2. The structure specified in claim 1, the outer end of said valve rod having a lateral bend forming a crank, and a link connected with said crank, said link being adapted for connection with the push-pull rod which is used for actuating said throttle valve.

3. The structure specified in claim 1, in conjunction with a discharge pipe connected with said neck and adapted for connection with an adjacent portion of the intake manifold, and a pickup and supply pipe connected at one end with the elbow and adapted for connection at its opposite end with the filler neck of the stated fuel storage tank.
